UNITED STATES PATENT OFFICE.

ARTHUR R. HAVENER, OF WAYLAND, MASSACHUSETTS, ASSIGNOR TO JUDSON L. THOMSON MFG. CO., A CORPORATION OF MASSACHUSETTS.

SHIPPING-CASE-RIVETING MACHINE.

1,407,859.

Specification of Letters Patent. Patented Feb. 28, 1922.

Application filed December 1, 1920. Serial No. 427,522.

To all whom it may concern:

Be it known that I, ARTHUR R. HAVENER, a citizen of the United States, residing at Wayland, in the county of Middlesex and 5 State of Massachusetts, have invented new and useful Improvements in Shipping-Case-Riveting Machines, of which the following is a specification.

This invention relates to machines for 10 attaching together by means of metallic fasteners, preferably bifurcated rivets, the closing flaps of a shipping case, these cases being made of fibre, pasteboard or the like.

The object of the invention is to provide 15 a simple, convenient and easily operated machine whereby the flaps of a shipping case may be firmly connected together by metallic fasteners such as rivets.

The invention consists in the combination 20 and arrangement of parts set forth in the following specification and particularly pointed out in the claims.

Referring to the drawings:

Figure 1 is a side elevation of a portion 25 of a riveting machine of well known construction with my improved attachment for riveting shipping cases shown in connection therewith, a shipping case being shown in section in position to be operated upon by 30 said machine.

Fig. 2 is a sectional plan taken on line 2-2, Fig. 1, the same being broken away to save space in the drawings.

Fig. 3 is a front elevation of the head of a 35 riveting machine such as is shown in Fig. 1, together with the work support and with a shipping case shown in position for riveting and positioned relatively to the improved attachment which forms a part of this invention.

Fig. 4 is a plan view of a shipping case after the same has been riveted by the machine of this invention.

In the drawings, 5 is the frame of the machine, 6 the head, 7 the driver, 8 the rivet holder, 9 the work support, 10 a screw by means of which the work support may be raised and lowered, the said work support being provided in its upper face with balls 11 45 upon which the shipping case 12 rests during the riveting operation. An anvil 13 is provided which is fastened to a horizontally disposed anvil blade 14. The front end of the anvil blade 14 is fastened to a bracket 15, said 50 bracket being mounted to rotate upon a stud

16 constituting a pivot. The stud 16 passes upwardly from the bracket 15 through a sleeve 17 which is fastened by means of a nut 18 having screw-threaded engagement with the upper end of the stud 16 to a right angle 60 support 19 which is fastened by screws 20 to the head of the machine. The lower end of the bracket 15 is bent to form a V 21, said V having two legs 22 and 23, the leg 23 having a recess 24 therein adapted to receive 65 one flap 25 of the case 12. Another flap 26 is adapted to project into a recess 27 formed by the legs 22 and 23 of the V shaped portion of the bracket. The front end of the anvil blade 14 is fastened to the underside 70 of the portion of the leg 23 which is located beneath the recess 24. It will, therefore, be seen that the lower portion of the bracket 15 constitutes a foot which not only supports the front end of the anvil blade, but also 75 provides means whereby the flaps 25 and 26 may be guided during the riveting operations. The rear end of the anvil blade 14 is adapted to be supported upon a stationary bracket 28 which is fastened to the frame of 80 the machine, see Figs. 1 and 2. The arm 14 is locked in the position illustrated in Fig. 2, that is in operative position, by means of a pin 29 which is fastened to an arm 30, said arm being pivoted at 31 to the underside of 85 the horizontal portion of the bracket 28. The pin 29 projects upwardly from the arm 30 through a slot 32 in the horizontal portion of said stationary bracket 28 and into a notch 33 provided in the rear edge of the 90 anvil blade 14. Another pin 34 fast to said stationary bracket 28 forms a stop with which the anvil blade 14 contacts when in operative position. A portion 35 of the rear edge of the anvil blade is inclined for a purpose hereinafter described. The arm 30 is held in the position illustrated in Fig. 2 by a spring 36, one end of which is fastened to a pin 37 on said arm, the other end of which is fastened to a pin 38 fast to the head 100 of the machine. A convexly curved plate 39 has a shank 40 thereon which extends through the free end of the arm 30 and is held in said arm by a set screw 41. The object of the mechanism just described is to 105 provide a means for locking the pivoted anvil blade in operative position, which means is also adapted to be operated by the contact therewith of the case being riveted to unlock the anvil blade and allow the same 110

to be swung upon its pivot to one side and thus allow the case to be removed therefrom after the riveting operations have been performed.

5 It will be noted that the anvil is located upon the anvil blade intermediate the pivotal stud 16 adjacent the front end of the anvil blade and the stationary supporting bracket 28 which is adapted to support the 10 rear end of the anvil blade.

The general operation of the mechanism hereinbefore specifically described is as follows: The case 12 is placed upon the work support 9 with the flap 25 projecting into the recess 24 and the flap 26 projecting into the recess 27. With the anvil blade in the position illustrated in Fig. 2 the machine is then operated to drive a rivet 42 through the flaps 25 and 26 and clinch the same in 15 the usual manner upon the anvil 13. The operator then moves the case along the anvil blade 14 toward the rear end thereof the correct distance and then operates the machine to drive successively rivets 43, 44 and 20 45 through the flaps 25 and 26. After the last rivet 45 has been driven, the operator moves the case a little further toward the rear of the anvil blade, thus bringing one end of said case into contact with the plate 39 which causes the arm 30 to be swung upon 25 its pivot in the direction of the arrow *a*, Fig. 2, thus the pin 29 will move out of the notch 33 and the anvil blade will then be free to be swung in the direction of the arrow *b*, Fig. 2, until it is brought to a position 30 where the case can be slid off of the anvil blade. The anvil blade is then swung back in a direction reverse to the arrow *b*, the inclined edge 35 will strike the pin 29 and will 35 swing the arm 30 upon its pivot 31 in the direction of the arrow *a* until the anvil blade engages the stop pin 34, whereupon the pin 29 will be caused to enter the notch 33 by the action of the spring 36 and the parts are 40 then in position for another case to be operated upon.

I claim:

1. A shipping case riveting machine having, in combination, a horizontally disposed 50 anvil blade, a pivot upon which the front end of said anvil blade is mounted and a stationary support upon which the rear end of said anvil blade is adapted to be supported and riveting instrumentalities positioned adjacent to said anvil blade and intermediate said pivot and support, means to lock said anvil blade to said support, and means adapted to be manually operated by 55

movement of a case on said anvil blade to unlock said anvil blade so as to allow the 60 same to be swung on said pivot to allow said case to be removed from said anvil blade.

2. A shipping case riveting machine having, in combination, a horizontally disposed anvil blade, a stationary support upon which 65 the rear end of said anvil blade is adapted to be supported, a pivot, flap positioning means for the flaps of said case mounted on said pivot and fastened to the front end of said anvil blade and riveting instrumentalities 70 positioned adjacent to said anvil blade and intermediate said pivot and support.

3. A shipping case riveting machine having, in combination, a horizontally disposed anvil blade, a stationary support upon which 75 the rear end of said anvil blade is adapted to be supported, a pivot, and a bracket having a flap receiving recess extending thereacross adjacent its lower end; fast to said pivot and projecting downwardly therefrom to which the front end of said anvil 80 blade is fastened.

4. A shipping case riveting machine, having, in combination, a horizontally disposed anvil blade, a stationary support upon which 85 the rear end of said anvil blade is adapted to be supported, a pivot, and a bracket having a pair of flap receiving recesses extending thereacross adjacent its lower end; fast to said pivot and projecting downwardly therefrom to which the front end of said anvil 90 blade is fastened.

5. A shipping case riveting machine, having, in combination, a horizontally disposed anvil blade, a stationary support upon which 95 the rear end of said anvil blade is adapted to be supported, a pivot, a bracket fast to said pivot and projecting downwardly therefrom to which the front end of said anvil blade is fastened, the lower end of said bracket terminating in a horizontally disposed V-shaped foot and one leg of said V being fastened to the upper face of said anvil blade so as to provide a recess to enable one flap of said case to project thereinto while another flap 105 of said case is positioned between the legs of said V.

In testimony whereof I have hereunto set my hand in presence of two subscribing witnesses.

ARTHUR R. HAVENER.
